FRAZER W. GAY, OF NEWARK, NEW JERSEY

REFRIGERATING METHOD AND MACHINE

Application filed March 27, 1928. Serial No. 265,134.

This invention relates in general to so-called mechanical refrigerating methods and machines. In known methods and machines of this character a refrigerant gas is compressed in a cylinder, liquefied in a condenser, the liquid thus formed is valved into an expansion chamber where it is vaporized, and the vapor is then returned to the compression cylinder. Many valves and stuffing boxes are employed which are unreliable and require careful attention of a mechanic to maintain continued operation.

Among the objects of my invention are to provide a method and machine of the general character described eliminating the necessity for said multiplicity of valves and other unreliable parts, and including in their stead, a simple, efficient and reliable heat transferring valve comprising a single hermetically sealed chamber wherein the refrigerant vapor is successively subjected to compression, condensation and volatilization or vaporization and through which heat is extracted and conveyed from the chamber to be cooled.

Other objects are to provide a refrigerating machine of this character including a chamber for a refrigerant liquid, the walls of which can be collapsed and expanded to vary the capacity of the chamber and cause compression and expansion of the refrigerant vapor, the bottom or floor of said chamber forming a part of the roof or ceiling of the vessel from which it is desired to extract heat and the top or roof of said chamber serving as a condenser; to provide a novel and improved combination and arrangement of a plurality of such chambers whereby great efficiency in heat exchange is obtained, and to obtain other advantages and results as will more fully appear from the following description.

My invention in its simplest form embodies only one chamber, but in the preferred form illustrated in the accompanying drawings, two chambers are utilized and arranged in tandem so that as one is expanded and collapsed the other is simultaneously collapsed and expanded respectively and by the same operating means.

Referring to said drawings in which cor-

responding and like parts are designated throughout the several views by the same reference characters,

Figure 1 is a side elevation of the refrigerating machine;

Figure 2 is an enlarged vertical sectional view taken on the line 2—2 of Figure 1;

Figure 3 is an end elevation viewing the machine from line 3—3 of Figure 1,

Figure 4 is a schematic sectional elevation of another form of the invention, and

Figure 5 is a schematic view of operating means for the compressing and expanding chambers.

Specifically describing the embodiment of my invention illustrated in Figures 1 to 3, inclusive, of the drawings, the reference character A designates a refrigerator having the usual heat insulating walls, and in which are provided the usual shelves B for supporting articles of food. A shelf C is also provided for supporting a tank D containing brine E. Submerged in the brine is a vessel 1 having a reduced neck portion extending upwardly through the top of the refrigerator and terminating in a compartment 3 comprising a bottom wall 4, top wall 5 and a side wall 6. This compartment is preferably substantially circular in plan view and a portion of the top wall 5 is in the form of a cup 7 depending into the compartment 3, as clearly shown in Figure 2 of the drawings. The wall 5 serves both as a roof for the compartment 3 and the bottom or floor of the valve chamber 8 whose side walls 9 are shown as elastic or flexible so as to be expandable and collapsible to vary the capacity of the chamber. As shown, the side walls 9 form what is commonly known as a sylphon. The chamber 8 also has a top or roof wall 10 which also forms the bottom or floor of a second valve chamber 11 coaxial with but somewhat smaller than the chamber 8. The wall 10 thus constitutes a partition between the chambers 8 and 11, and it has a cup 12 depending therefrom into the chamber 8 and adapted to telescopically enter the cup 7. The side walls 13 of the chamber 11 are of the same formation as the walls 9 of the chamber 8 so that the capacity of the cham-

55

75

80

85

90

100

ber 11 may be varied by expansion and contraction of the side walls. The chamber 11 has a top wall or roof 14 which is recessed to receive a container 15 for a volatile liquid 16, said wall being supported upon and connected to the wall 4 or top of the refrigerator A by standards 140. The bottom of said chamber 15 has a cup 17 extending through the wall 14 into the chamber 11. This 10 chamber 15 is also connected by a pipe 18 to a radiator 19 which serves to cool the vapors of the liquid 16 as hereinafter described.

Within the vessel 1, the chamber 8, and the chamber 11, are hermetically sealed substantially equal quantities of a suitable volatile refrigerant, preferably butane, and the liquid 16 is also preferably butane and hermetically sealed within the container 15, pipe 18 and radiator 19. In accordance with the 20 invention the partition 12 is alternately moved in opposite directions to compress the vapors of the volatile liquid in one of the chambers 8 and 11, and simultaneously expand or vaporize the refrigerant liquid in the other chamber, and it is during these 25 movements of the partition 12 that heat is extracted from the vessel 1 and conveyed through my heat transfer valve to the radiator 19 where it is dissipated into the atmosphere.

The partition 10 may be actuated by any suitable means but I have shown a cross-head 20 connected to said partition and extending upwardly thereabove and connected at 21 to one end of a connecting rod or pitman 22, the other end of which is journaled on a crank pin 23 attached to a crank disc 24 journaled on a shaft 25, the periphery of which is in the form of a gear 26 which 30 meshes with a pinion 27 on the shaft of an electric motor 28 supported on a suitable standard or pedestal 29 on the top of the refrigerator A. The motor 28 also drives a fan 30 for forcing air through the air passages of the radiator 19 and preferably a ring 31 is attached to the extremity of the fan blades to serve as a flywheel. With this construction it will be observed that the partition 12 will be constantly reciprocated by 40 the motor 28, and thereby the capacities of the two valve chambers 8 and 11 are simultaneously varied.

In operation of my heat transfer valve and assuming that the position of the partition is such as to make the chamber 11 of maximum capacity, the volatile refrigerant in the chamber will be in vaporous form. As the partition 10 is moved toward the wall 14, the sides 13 of the chamber 11 are collapsed and the capacity of said chamber reduced. This compresses the vapors in the chamber to a high pressure and with the increasing temperature the latent heat in the vapors will be transferred through the 55 cup 17 to the volatile liquid 16 in the con-

tainer 15. During this transfer of heat, the vapors will be condensed and drip into and partially fill the cup 12 as the latter approaches the dotted line position of Figure 2. Obviously the butane in the cup 7 will have been volatilized by the simultaneous expansion of the chamber 8. The partition 10 is then moved in the other direction toward the bottom wall 5 of the chamber 8, whereupon the capacity of said chamber 8 is reduced and the capacity of the chamber 11 70 increased. It will be evident, therefore, that the vapor in the chamber 8 will thereby be compressed and condensed which action takes place in the following manner. As the partition 10 starts toward the wall 5, a partial vacuum is formed by the enlarged volume of the chamber 11 and this gradually increasing capacity is constantly compensated by volatilization of the liquid in the cup 12 to fill the chamber. The temperature of the cup 12 and the liquid therein rapidly falls by reason of the giving up of heat by the liquid to vaporize the liquid. At the same time the pressure and temperature in the chamber 8 rapidly increases due to its diminishing capacity; and the temperature of the cup 12 is soon so low and the pressure of the vapor in the chamber 8 is so high, that 80 said vapor is condensed on the lower side of the cup 12, at the same time giving up its latent heat to volatilize the liquid in the cup 12. During the remainder of the movement of the partition 10 toward the bottom 5 of the chamber 8, the temperature and pressure 85 in both the chambers 8 and 11 remains substantially constant until most or all of the vapor in the lower chamber 8 has been condensed on the cup 12 and dripped down and partially filled the cup 7, and most if not all 90 of the liquid in the cup 12 has been volatilized. At the end of this movement the cup 12 is in the dotted line position of Figure 2, and thereupon the movement of the partition 10 is reversed and it rises slowly toward the top wall 14 of the chamber 11. Immediately the volatile liquid in the cup 7, boils, and its vapor compensates the increasing capacity of the chamber 8. Thereupon, the temperature of the cup 7 and its 100 liquid falls until it is below the temperature of the liquid in the vessel 6, (see Figure 1), 105 the vapor of which is in contact with the underside of the cup 7. The liquid in the vessel 1 now boils, and its vapor condenses on the 110 underside of the cup 7, giving up its latent heat to the liquid in the cup 7. The vapor in the chamber 11 increases in pressure and temperature until it condenses on the underside of the cup 17 and transfers its heat to 115 the liquid 16 in said cup and the container 15. The vapors of the liquid 16 thus produced are conducted through the pipe 18 to the radiator 19 where they are cooled by the 120 fan 30. The operation is then repeated. 130

It is possible to separate the heat transferring elements from the compressing and expanding elements, that is it is possible to arrange the cups 7, 12 and 17 in chambers of unvarying capacity and to compress the refrigerant vapors in separate devices, and conduct the refrigerant vapors from said devices to the heat transferring elements. An illustration of this form of the invention is found in Figure 4 of the drawings, where a casing 32 is transversely divided by the partitions 33, 34, and 35 into a plurality of chambers 36, 37, 38 and 39. The chamber 39 communicates with its floor or bottom through a conduit 40 with the vessel 1. The partitions 33, 34, 35 have respective central cup-like portions 41, 42 and 43. The chamber 36 contains a volatile liquid 44 corresponding to the liquid 16, while the cups 42 and 43 contain substantially equal quantities of a refrigerant, for example, butane. The chambers 37 and 38 are respectively connected to sylphons 45 and 46 which may be expanded and contracted by any suitable means such as by a walking-beam 47 pivotally mounted intermediate its ends on a fixed support as at 48 and having its ends connected to the top walls of the respective sylphons as shown in Figure 5 of the drawings. The walking-beam may be oscillated by any suitable means through a link 49.

With this construction it will be observed that the butane in the chambers 37 and 38 will be alternately compressed and expanded by operation of the sylphons 45 and 46: and when the vapors in the chamber 37 are compressed they give up their latent heat of evaporation to the liquid 44 and are condensed on the outside of the cup 41, while when the vapors in the chamber 38 are compressed they give up their latent heat to the liquid in the cup 42 and are condensed by the decreasing temperature of the vapors in the chamber 37, as the vapors therein are expanded simultaneously with the compression of the vapors in the chamber 38. When the liquid in the vessel 1 boils the vapors thereof give up their heat to the liquid in the cup 43 and condenses on the underside of said cup. It will be evident, therefore, that the operation of this form of the invention is the same as that of the construction shown in Figures 1 to 3, inclusive, the main difference being in the construction and combination of the apparatus.

The vessel 1 and its tube serves in both forms as a heat valve to permit flow of heat from the brine E to the chamber 8 and prevent flow of heat in the other direction.

It should be understood that other means than the sylphons may be utilized for compressing and expanding the refrigerant, for example rubber bulbs which are alternately compressed and permitted to expand might be used; and other means for actuating the

compressing and expanding means might be utilized in place of the motor 28 and its connections to the partition 10, or the walking-beam 47 of Figures 4 and 5. Instead of using butane or the like and the radiator 19, it is possible to obtain good results by merely circulating cool water through the container 15. Other modifications within the scope of the invention, will readily occur to those skilled in the art. 70

Having thus described my invention what I claim is:

1. The method of transferring heat from a cold body to a relatively hot body, consisting in alternately decreasing and increasing the pressure of a refrigerant in contact with both said cold body and said hot body so that said refrigerant in the form of a liquid at a low temperature contacts only with said cold body and boils so as to remove heat from said cold body, and said refrigerant in vaporous state contacts only with and condenses upon said hot body so that the refrigerant gives up its heat to said hot body. 75

2. The method of transferring heat from a cold body to a relatively hot body, consisting in alternately decreasing and increasing the pressure of a refrigerant in contact with body said cold body and said hot body so that said refrigerant in the form of a liquid at a low temperature contacts only with said cold body and boils so as to remove heat from said cold body, and said refrigerant in vaporous state contacts only with and condenses upon said hot body so that the refrigerant gives up its heat to said hot body, and insulating by another gas said cold body from said refrigerant when the latter is hot. 90

3. A heat transferring device, comprising a bodily stationary chamber to contain refrigerant vapors having elastic side walls, a top wall in contact with the medium to which it is desired to transfer heat and a bottom wall in contact with the medium from which it is desired to transfer heat, and means for extending and collapsing said elastic walls to vary the capacity of said chamber so that the refrigerant is alternately raised to a pressure sufficient to condense it and expanded sufficiently to permit volatilization thereof. 100

4. The method of transferring heat from a medium at low temperature to a medium at high temperature, consisting in successively increasing and decreasing the volume of a hermetically enclosed refrigerant to alternately compress it sufficiently to condense it and expand it sufficiently to volatilize it, and causing said refrigerant to contact by action of gravity in vaporous condition with said hot medium and in liquid condition with said cold medium. 120

5. A device for transferring heat from a medium at low temperature to a medium at higher temperature, comprising a hermetically sealed chamber having a refrigerant there- 130

in, means for successively increasing and decreasing the volume of said refrigerant to alternately change it from a liquid to a gas and vice versa, said chamber having a top portion of the walls thereof in juxtaposition with the medium at higher temperature to which heat is to be transferred, and a bottom cupped portion in juxtaposition with the medium at low temperature from which heat is to be transferred.

6. A device for transferring heat from a medium at low temperature to a medium at higher temperature, comprising a hermetically sealed chamber having a refrigerant therein, means for successively increasing and decreasing the volume of said refrigerant to alternately change it from a liquid to a gas and vice versa, said chamber having a top portion of the walls thereof in juxtaposition with the medium at higher temperature to which heat is to be transferred, a bottom cupped portion in juxtaposition with the medium at low temperature from which heat is to be transferred, and a heat valve between said low temperature medium and the cupped portion of the bottom wall of said chamber adapted to allow the free passage of heat from said low temperature medium to said bottom wall but acting as a heat insulator to the flow of heat from said bottom wall to said low temperature medium.

7. The method of transferring heat from a body of refrigerant at a low temperature to a higher body of refrigerant at a high temperature by interposing an intermediate body of refrigerant between said bodies to contact with both thereof, and alternately compressing said intermediate body of refrigerant to small volume and expanding it to relatively large volume.

8. A heat valve, consisting of an expandible and contractible hermetically sealed chamber containing a volatile liquid and its vapors, a cold vessel beneath said chamber and a relatively hot vessel above said chamber, both vessels to contact with said chamber to facilitate the rapid passage of heat vertically upward, and means to expand and contract said chamber to vary the volume thereof.

9. A device for transferring heat from a low temperature body to an ambient cooling medium, comprising a hermetically sealed chamber containing a refrigerant and having a cupped bottom to accumulate said refrigerant as a liquid and contacting with a top portion of said low temperature body, means for successively increasing and decreasing the volume of said hermetically sealed chamber whereby during decreasing of said volume the pressure and temperature of said refrigerant is increased and upon the increasing of the volume of said chamber a portion of said condensed refrigerant volatilizes, means to expedite the flow of

heat from the upper walls of said chamber whereby said refrigerant is condensed and flows to said cupped bottom, and a volatile refrigerant means in said cold body adapted to facilitate the rapid flow of heat from said cold body to the cupped bottom of said sealed chamber.

10. A refrigerator containing a refrigerant gas, a chamber having an outer lower portion in contact with said refrigerant gas from which it extracts heat by condensing said gas and an upper portion adapted to radiate heat, said chamber containing the vapor of a second body of volatile liquid, and means for increasing and decreasing the pressure of said second vapor in said chamber so that during periods of high pressure said vapor condenses to a liquid on the radiator portion of said chamber and runs down into said lower portion where it volatilizes when pressure of said vapor is reduced and thereby cools its outer lower portions so that the first-mentioned refrigerant gas gives up its heat to said lower portions and condenses thereon and falls back into said refrigerator.

11. The method of transferring heat from a cold body to a hot body, consisting in arranging said bodies in vertically spaced relation with the hot body uppermost, interposing therebetween in contact with both thereof an intermediate enclosed body of refrigerant adapted to have its temperature raised by volume expansion and contraction through a range from lower than said cold body to higher than said hot body, and alternately increasing and decreasing the volume of said refrigerant so that each of the three bodies facilitates the rapid passage of heat upward by the volatilization of said refrigerant in liquid form and the condensation of said refrigerant in vaporous form.

12. The method of transferring heat consisting in successively compressing and expanding vapors of a refrigerant in one chamber and simultaneously expanding and compressing other vapors of a refrigerant in another chamber having a portion of its bottom in contact with the first mentioned vapors, causing contact of the walls of one of said chambers with vapors of a volatile liquid enclosed in a vessel which is in contact with the medium to be cooled, and removing heat from the other chamber from the outside of a wall thereof.

13. A heat transferring device comprising two aligned chambers each to contain refrigerant vapors and having one common wall, and means for compressing and expanding the refrigerant vapors which are in one chamber and simultaneously expanding and compressing respectively the refrigerant vapors which are in the other chamber.

14. A heat transferring device comprising two aligned chambers each to contain refrigerant vapors and having one stationary end

- wall and another end wall common to both chambers, said chambers also having independent elastic side walls connecting said common wall to the respective stationary end walls, and means for reciprocating said common wall to increase and decrease the capacity of one chamber and simultaneously respectively decrease and increase the capacity of the other chamber. 5
15. A heat transferring device comprising a chamber to contain refrigerant vapors, a vessel containing a volatile liquid in contact with the medium from which heat is to be transferred and arranged so that its vapors may contact with a portion of the walls of said chamber, a second vessel containing volatile liquid in contact with another portion of the walls of said chamber and so arranged that its vapors can contact with the medium to which the heat is to be transferred, and mechanical means for increasing and decreasing the pressure in said chamber so that the pressure of the refrigerant is alternately raised sufficiently to condense the refrigerant and expanded sufficiently to permit volatilization of the refrigerant. 10
16. A refrigerating machine comprising a refrigerator heat insulated casing, a tank containing brine within said casing, a hermetically sealed vessel dipping into said brine and containing a refrigerant liquid, a chamber containing refrigerant vapors, said chamber and said vessel being so arranged that the vapors of each can contact with opposite sides of a common wall, means for alternately compressing and expanding the vapors in said chamber, a second vessel containing a refrigerant liquid and so arranged with respect to said chamber that the vapors in said second vessel and said chamber contact with opposite sides of a common wall, and means for cooling the vapors in said second vessel. 15
17. A refrigerating machine comprising a refrigerator heat insulated casing, a tank containing brine within said casing, a hermetically sealed vessel dipping into said brine and containing a refrigerant liquid, two aligned chambers each to contain refrigerant vapors and having one common wall, one of said chambers and said vessel being so arranged that vapors in each can contact with opposite sides of a wall common to both said chambers and said vessel, means for compressing and expanding the refrigerant vapors which are in one chamber and simultaneously respectively expanding and compressing the vapors which are in the other chamber, and a second container for refrigerant liquid so arranged with respect to the other of said chambers that the vapors in said chamber and said container contact with a wall common to both the second chamber and said container, and means for cooling the vapors in said container. 20
18. In a heat transferring device, two ad-
- jacents chambers having a horizontally disposed wall in common, means for successively compressing and liquefying at high temperature and expanding and volatilizing at low temperature a refrigerant in one chamber and simultaneously expanding and volatilizing at low temperature and compressing and liquefying at high temperature, a refrigerant in the other chamber said chambers being disposed vertically and the bottom of said chambers being in contact with a cold body adapted to allow heat to flow through said bottom into said chambers by condensation of vapors on said bottom when said bottom is cold but to substantially prevent flow of heat from said bottom to said cold body through said heat insulating vapors when said bottom is hot, and means in contact with the uppermost wall of said chambers adapted to absorb heat. 25
